CABINET DOOR PULL

Lawrence McCain, Beverly Hills, and Raymond Tintary, Covina, Calif., assignors to Ajax Hardware Manufacturing Corp., City of Industry, Calif., a corporation of California

Filed Nov. 3, 1969, Ser. No. 19,917

Term of patent 14 years

Int. Cl. D8—03

U.S. Cl. D8—166

FIG. 1 is a front elevational view of a cabinet door pull;

FIG. 2 is a side elevational view;

FIG. 3 is a vertical sectional view taken on the broken line 3—3 of FIG. 1; and

FIG. 4 is a rear elevational view;

FIG. 5 is a top plan view; and

FIG. 6 is a transverse sectional view taken on the broken line 6—6 of FIG. 1.

We claim:

The ornamental design for a cabinet door pull, as shown.
